[57] ABSTRACT

The invention concerns new dibenzothiepines of the formula:

wherein R is alkyl of one to four carbon atoms and n is 1 or 2, or

R is alkyl of two to four carbon atoms and n is 0, and pharmaceutically acceptable acid addition salts thereof. The compounds are useful in the prophylaxis and treatment of gastric ulcers.

5 Claims, No Drawings

CERTAIN 6,11-DIHYDRO-11-(3-ALPHA-TROPANYLOXY)-DIBENZO[B,E]THIEPINE-5-OXIDES AND THE CORRESPONDING DIOXIDES AND DERIVATIVES THEREOF

IMPROVEMENTS IN OR RELATING TO ORGANIC COMPOUNDS

This invention relates to dibenzothiepine derivatives. In accordance with the invention there are provided new dibenzothiepines of formula I,

wherein R is alkyl of one to four carbon atoms and n is 25

is 1 or 2, or

R is alkyl of two to four carbon atoms and n is 0, and acid addition salts thereof.

Further, in accordance with the invention a compound of formula I is obtained by a process comprising

30

a. reacting a compound of formula III,

wherein R is alkyl of one to four carbon atoms, 40 with a compound of formula II,

wherein n is 1 or 2, or, when R in the compound of formula III is alkyl of two to four carbon atoms, n is 0, and

X is the acid radical of a reactive ester, in the presence of an inert organic solvent, or

b. reacting a compound of formula Ia,

1a

wherein R' is alkyl of two to four carbon atoms, in neutral or weakly acid solution, with an alkali metal salt or alkaline earth metal salt of periodic acid, or with the stoichiometric amount of an organic peracid or with the stoichiometric amount of hydrogen peroxide, to obtain a compound of formula Ib,

1b

wherein R is alkyl of one to four carbon atoms, 20 c. oxidizing a compound of formula Ia or Ib in acid solution with hydrogen peroxide or an organic peracid to a compound of formula Ic,

1c

wherein R is alkyl of one to four carbon atoms, 40 and, where an acid addition salt is required, converting the resulting compound of formula I into such salt.

In the claims, the dibenzothiepines of formula I have been defined by the formulae:

45

II 50

60

Process variant (a) may, for example, be effected as follows: A solution of a compound of formula II, wherein X is preferably chlorine, bromine, iodine or fluorine, or the radical of an organic sulphonate acid, in an inert solvent, e.g., an aromatic hydrocarbon such as absolute toluene or absolute benzene, is added dropwise at an elevated temperature, conveniently under reflux at the boiling temperature of the reaction mixture, optionally in the presence of an acid-binding

65

agent, e.g., an alkali metal carbonate such as sodium or potassium carbonate, or a tertiary organic base such as triethylamine, to a solution of a nortropine or pseudonortropine alkyl derivative (nortropan-3 α -ol or nortropan-3 β -ol derivatives) in the same solvent.

Process variant (b) is preferably effected at a low temperature, preferably between 0° and 50° C, and optionally in an inert solvent, e.g., acetic acid or acetone. Reaction times under preferred conditions are of the order of 10 to 20 hours.

Process variant (c) is preferably effected using an excess of hydrogen peroxide or an organic peracid. An inert solvent, e.g., glacial acetic acid or acetone, is preferably used. The reaction is suitably carried out at an elevated temperature, preferably at a temperature between about 50° and 150° C, and may have a duration of about 3 to 10 hours under preferred conditions.

The resulting compounds of formula I may be worked up and optionally purified in accordance with known methods.

In the process of the invention the steric configuration remains unchanged, so that, e.g., when nortropan-3 α -ol derivatives are used in accordance with embodiment (a) of the process, the corresponding 11-(8-alkyl-3 α -nortropanyloxy)-6,11-dihydrodibenzo-[b,e]thiepine derivatives are obtained, and this configuration is also maintained in the case of an oxidation in accordance with process variants (b) and (c).

The preferred compounds of formula II may be obtained as follows:

a'. a compound of formula IIa,

wherein n is 0, 1 or 2, and

X^1 is the radical of an organic sulphonate acid, is produced by reacting a compound of formula IV,

wherein n is 0, 1 or 2, with an organic sulphonate acid halide in an inert solvent, or

b'. a compound of formula IIb,

wherein n is 0, 1 or 2, and

X'' is chlorine, bromine or iodine, is produced by passing hydrogen chloride, bromide or iodide through a solution of a compound of formula IV

in an inert solvent, or
c'. a compound of formula IIc,

IIc

5 10 wherein n is 0, 1 or 2, is produced by reacting a compound of formula IIId,

IIId

15 20 wherein n is 0, 1 or 2, and X''' is chlorine or bromine, with a metal fluoride, or

d'. a compound of formula IIb is produced by reacting a compound of formula IV with thionyl chloride or bromide, or phosphorus chloride, bromide or iodide.

25 30 Process (a') is preferably carried out in a basic medium and an organic basic solvent, e.g., pyridine, or a lower trialkylamine such as triethylamine, is preferably used as inert solvent, or the reaction is effected in an inert organic solvent with the addition of pyridine or a lower trialkylamine.

An anhydrous aromatic hydrocarbon such as benzene may, for example, be used as solvent in process (b'). The 11-iodo derivative may likewise be produced from the 11-bromo derivative by reaction with sodium iodide in acetone.

In process (d') phosphorus trichloride, tribromide or pentachloride may, for example, be used as phosphorus 40 halide.

A compound of formula IIe,

IIe

45 50 wherein X is as defined above, may likewise be obtained by reacting a compound of formula IIIf,

IIIf

55 60 wherein X is as defined above, in neutral or weakly acid solution, with an alkali or alkaline earth salt of periodic acid, or with the stoichiometric amount of an organic peracid or with 65 the stoichiometric amount of hydrogen peroxide, in a manner analogous to process variant (b) for the production of compounds of formula Ib.

A compound of formula IIg,

11g

wherein X is as defined above, may be obtained by oxidizing a compound of formula IIe or II_f in acid solution with hydrogen peroxide or an organic peracid, in a manner analogous to embodiment (c) of the process for the production of compounds of formula Ic.

A compound of formula Ia may be obtained by reacting a compound of formula II_f with a compound of formula III in accordance with process variant (a).

Insofar as the production of the starting materials is not particularly described, these are known or may be produced in accordance with known processes or in a manner analogous to the processes described herein or to known processes.

The compounds of formula I and pharmaceutically acceptable acid addition salts thereof are useful because they possess pharmacological activity in animals. In particular, the compounds are useful in the prophylaxis and treatment of gastric ulcers as indicated by the anticholinergic and histaminolytic tests in guinea pigs, the mydriasis test in mice, and further by an inhibition of phenylbutazone-induced ulcer formation in rats.

For the above mentioned use, the dosage administered will, of course, vary depending upon the compound employed, the mode of administration and the treatment desired. However, in general, satisfactory results are obtained when administered at a daily dosage of from about 0.05 to about 10 mg per kilogram animal body weight, conveniently given in divided doses 2 to 3 times a day, or in sustained release form. For the larger mammals, the total daily dosage is in the range of from about 2 to 10 mg, and dosage forms suitable for oral administration comprise from about 0.6 to about 5 mg of the compound, in association with a solid or liquid pharmaceutical carrier or diluent.

The compounds of formula I may be administered in pharmaceutically acceptable acid addition salt form. Such salts possess the same order of activity as the free bases and are readily prepared in conventional manner. Suitable such salt forms include mineral acid salts such as the hydrochloride, hydrobromide and sulphate, and organic acid salts such as the fumarate, maleate, tartrate, methane-, ethane- and benzene-sulphonate, citrate and malate.

The invention also provides a pharmaceutical composition comprising as active agent a compound of formula I, or pharmaceutically acceptable acid addition salt thereof, in association with a pharmaceutically acceptable carrier or diluent.

In the following non-limitative Examples all temperatures are indicated in degrees centigrade and are uncorrected.

EXAMPLE 1

11-(8-Ethyl-3 α -nortropanyloxy)-6,11-dihydrodibenzo[b,e]thiepine [process variant (a)]

Hydrogen chloride is passed through 22.7 g of 6,11-dihydrodibenzo[b,e]thiepin-11-ol in 50 cc of absolute

6

benzene for 15 minutes while cooling with ice. The solution is subsequently concentrated completely, the residue is dissolved in 50 cc of absolute benzene, is dried over magnesium sulphate and again concentrated completely. The crude 11-chloro-6,11-dihydrodibenzo-[b,e]thiepine is then dissolved in 80 cc of absolute xylene, and this solution is added dropwise to a boiling solution of 15.5 g of N-ethyl-nortropine in 50 cc of absolute xylene over a period of 15 minutes. The reaction mixture is then heated to the boil under reflux for 1 hour, is cooled to room temperature, diluted with 100 cc of diethyl ether and extracted twice with 50 cc amounts of 2 N hydrochloric acid. The aqueous extract is rendered alkaline with 2 N caustic soda solution, is extracted thrice with 100 cc amounts of ether, the combined ether extracts are dried over magnesium sulphate, purified with animal charcoal, and the solvent is completely distilled off. The oily residue, i.e., the title compound, is converted into the methanesulphonate, which has an M.P. of 198°-200° after recrystallization from ethanol.

EXAMPLE 2

6,11-Dihydro-11-(8-n-propyl-3 α -nortropanyloxy)-dibenzo[b,e]thiepine

6,11-Dihydrodibenzo[b,e]thiepin-11-ol is reacted with hydrogen chloride to obtain 11-chloro-6,11-dihydrodibenzo[b,e]-thiepine and this is subsequently reacted with N-n-propyl-nortropine in accordance with the process described in Example 1. The hydrogen fumarate of the title compound has an M.P. of 203°-205°.

EXAMPLE 3

6,11-Dihydro-11-(8-isopropyl-3 α -nortropanyloxy)-dibenzo[b,e]thiepine

6,11-Dihydrodibenzo[b,e]thiepin-11-ol is reacted with hydrogen chloride to obtain 11-chloro-6,11-dihydrodibenzo[b,e]-thiepine and this is subsequently reacted with N-isopropyl-nortropine in accordance with the process described in Example 1. The title compound has an M.P. of 126°-127°.

EXAMPLE 4

11-(8-n-Butyl-3 α -nortropanyloxy)-6,11-dihydrodibenzo[b,e]thiepine

6,11-Dihydrodibenzo[b,e]thiepin-11-ol is reacted with hydrogen chloride to obtain 11-chloro-6,11-dihydrodibenzo[b,e]-thiepine and this is subsequently reacted with N-n-butyl-nortropine in accordance with the process described in Example 1. The hydrogen fumarate of the title compound has an M.P. of 230° (decomp.).

EXAMPLE 5

6,11-Dihydro-11-(3 α -tropanyloxy)-dibenzo[b,e]thiepine-5-oxide [process variant (a)]

Hydrogen chloride is passed through 24.3 g of 6,11-dihydro-11-hydroxy-dibenzo[b,e]thiepine-5-oxide in 50 cc of absolute benzene for 15 minutes while cooling with ice. The solution is subsequently concentrated completely, the residue is dissolved in 50 cc of absolute benzene, is dried over magnesium sulphate and again concentrated completely. The residue is then dissolved in 80 cc of absolute xylene and this solution is added

dropwise to a boiling solution of 14.1 g of tropine (tropan-3 α -ol) in 50 cc of absolute xylene over a period of 15 minutes. The reaction mixture is subsequently heated to the boil under reflux for 1 hour, is then cooled to room temperature, diluted with 100 cc of diethyl ether and extracted twice with 50 cc amounts of 2 N hydrochloric acid. The aqueous extract is then rendered alkaline with 2 N caustic soda solution, is extracted thrice with 100 cc amounts of ether, the combined ether extracts are dried over magnesium sulphate, purified with animal charcoal, and the solvent is completely distilled off. The oily residue, i.e., the title compound, is converted into the hydrogen fumarate, which has an M.P. of 125°-127° after recrystallization from methanol.

The starting material is obtained as follows:

2.8 cc of a 40 percent hydrogen peroxide solution are added to a solution of 7.2 g of 6,11-dihydrodibenzo[b,e]thiepin-11-ol in 45 cc of glacial acetic acid, and the mixture is stirred at room temperature for 17 hours. The reaction solution is subsequently diluted with 70 cc of water, is cooled and rendered alkaline with a 25 percent ammonia solution. The aqueous phase is extracted thrice with 100 cc amounts of ether, the combined ether extracts are dried over magnesium sulphate and the solvent is completely evaporated at reduced pressure. The residue is used for the next reaction without further purification.

EXAMPLE 6

6,11-Dihydro-11-(3 α -tropanyloxy)-dibenzo[b,e]thiepine-5,5-dioxide [process variant (a)]

7.3 g of thionyl chloride are added to 15.8 g of 6,11-dihydro-11-hydroxy-dibenzo[b,e]thiepine-5,5-dioxide in 40 cc of absolute xylene, and the mixture is heated to 70° for 1 hour. After cooling to room temperature, 3.0 g of calcium chloride are added and the xylene phase is filtered in the absence of moisture. The xylene phase is subsequently added dropwise within 15 minutes to a boiling mixture of 8.6 g of tropine and 24.6 g of sodium carbonate in 50 cc of absolute xylene. The reaction mixture is heated under reflux for 6 hours and after cooling, is diluted with 200 cc of diethyl ether and extracted twice with 100 cc amounts of water. The organic phase is extracted with 100 cc of N hydrochloric acid, the hydrochloric acid extract is rendered alkaline with 2 N caustic soda solution and is extracted thrice with 300 cc amounts of diethyl ether. The ether extract is dried over sodium sulphate, is subsequently concentrated and the oily residue is distilled, whereby the title compound distills over at 190°-200° and 0.02 mm of Hg.

EXAMPLE 7

6,11-Dihydro-11-(3 α -tropanyloxy)-dibenzo[b,e]thiepine-5-oxide [process variant (b)]

2.8 cc of a 40 percent hydrogen peroxide solution are added to a solution of 10.5 g of 6,11-dihydro-11-(3 α -tropanyloxy)dibenzo-[b,e]thiepine in 45 cc of glacial acetic acid, and the mixture is stirred at room temperature for 17 hours. The reaction solution is subsequently diluted with 70 cc of water, is cooled and

rendered alkaline with a 25 percent ammonia solution. The aqueous phase is extracted thrice with 100 cc amounts of ether, the combined ether extracts are dried over magnesium sulphate and the solvent is completely concentrated at reduced pressure. The oily residue, i.e., the title compound, is then converted into the hydrogen fumarate with fumaric acid in ethanol. After recrystallization from methanol the hydrogen fumarate of the title compound has an M.P. of 125°-127°.

The 6,11-dihydro-11-(3 α -tropanyloxy)dibenzo[b,e]thiepine, required as starting material, may be produced as follows:

7.3 g of thionyl chloride are added to 14.0 g of 6,11-dihydrodibenzo[b,e]thiepin-11-ol in 40 cc of absolute xylene, and the mixture is heated to 70° for 1 hour. After cooling to room temperature, 3.0 g of calcium chloride are added and the xylene phase is filtered in the absence of moisture. The xylene phase is subsequently added dropwise within 15 minutes to a boiling mixture of 8.6 g of tropine (tropan-3 α -ol) and 24.6 g of sodium carbonate in 50 cc of absolute xylene. The reaction mixture is heated under reflux for 6 hours and after cooling, is diluted with 200 cc of diethyl ether and extracted twice with 100 cc amounts of water. The organic phase is extracted with 100 cc of N hydrochloric acid, the hydrochloric acid extract is rendered alkaline with 2 N caustic soda solution and is extracted thrice with 300 cc amounts of diethyl ether. The ether extract is dried over sodium sulphate, is subsequently concentrated and the oily residue is distilled, whereby the title compound distills over at 190°-200° and 0.02 mm of Hg.

EXAMPLE 8

11-(8-Ethyl-3 α -nortropanyloxy)-6,11-dihydrodibenzo[b,e]thiepine-5-oxide

The title compound is obtained in accordance with the process described in Example 7 (c) 11-(8-ethyl-3 α -nortropanyloxy)-6,11-dihydrodibenzo[b,e]thiepine. The hydrogen fumarate of the title compound has an M.P. of 134° (Dec.)

EXAMPLE 9

6,11-Dihydro-11-(3 α -tropanyloxy)-dibenzo[b,e]thiepine-5,5-dioxide [process variant (c)]

5.6 cc of a 40 percent hydrogen peroxide solution are added to a solution of 10.5 g of 6,11-dihydro-11-(3 α -tropanyloxy)dibenzo-[b,e]thiepine in 45 cc of glacial acetic acid, and the mixture is heated in an oil bath of 80° for 7 hours. After cooling to room temperature, the mixture is diluted with 70 cc of water and the solution is rendered alkaline with a 25 percent ammonia solution while cooling. The aqueous phase is then extracted thrice with 200 cc amounts of chloroform, the combined chloroform phases are dried over magnesium sulphate and the solvent is distilled off at reduced pressure. The oily residue, i.e., the title compound, is then converted into the methanesulphonate with methanesulphonic acid in methanol. After recrystallization from methanol, the methanesulphonate of the title compound has an M.P. of 225°-230°.

EXAMPLE 10

11-(8-Ethyl-3 α -nortropanyloxy)-6,11-dihydrodibenzo

[b,e]thiepine-5,5-dioxide

The title compound is obtained by treating 11-(8-ethyl-3 α -nortropanyloxy)-6,11-dihydrodibenzo[b,e]thiepine with hydrogen peroxide in accordance with the process described in Example 9.

The hydrogen fumarate of the title compound has an M.P. of 157°-159° (decomp.).

EXAMPLE 11

6,11-Dihydro-11-(3 α -tropanyloxy)-dibenzo[b,e]thiepine-5,5-dioxide

The title compound is obtained by treating 6,11-dihydro-11-(3 α -tropanyloxy)dibenzo[b,e]thiepine-5-oxide with hydrogen peroxide in accordance with the process described in Example 9.

The methanesulphonate of the title compound has an M.P. of 225°-230°.

EXAMPLE 12

11-(8-Ethyl-3 α -nortropanyloxy)-6,11-dihydrodibenzo[b,e]thiepine-5,5-dioxide

The title compound is obtained by treating 11-(8-ethyl-3 α -nortropanyloxy)-6,11-dihydrodibenzo[b,e]thiepine-5-oxide with hydrogen peroxide in accordance with the process described in Example 9.

The hydrogen fumarate of the title compound has an M.P. of 157°-159° (decomp.).

What is claimed is:

1. A compound of the formula:

wherein R is alkyl of one to four carbon atoms, and m is 1 or 2,

or a pharmaceutically acceptable acid addition salt thereof.

2. The compound of claim 1, which is 6,11-dihydro-11-(3 α -tropanyloxy)dibenzo[b,e]thiepine-5-oxide.

3. The compound of claim 1, which is 6,11-dihydro-11-(3 α -tropanyloxy)dibenzo[b,e]thiepine-5,5-dioxide.

4. The compound of claim 1, which is 11-(8-ethyl-3 α -nortropanyloxy)-6,11-dihydro-dibenzo[b,e]thiepine-5-oxide.

5. The compound of claim 1, which is 11-(8-ethyl-3 α -nortropanyloxy)-6,11-dihydro-dibenzo[b,e]thiepine-5,5-dioxide.

* * * * *
